UNITED STATES PATENT OFFICE.

GEORGE W. BENEDICT, OF CINCINNATI, OHIO.

CARBURETER.

SPECIFICATION forming part of Letters Patent No. 622,198, dated April 4, 1899.

Application filed June 10, 1897. Serial No. 640,142. (No model.)

To all whom it may concern:

Be it known that I, GEORGE W. BENEDICT, a resident of Cincinnati, in the county of Hamilton and State of Ohio, have invented 5 certain new and useful Improvements in Incandescent Gas-Machines; and I do hereby declare the following to be a full, clear, and exact description of the invention, such as will enable others skilled in the art to which 10 it appertains to make and use the same.

My invention relates to an improvement in incandescent gas-machines, the object being to provide an apparatus which will manufacture gas from hydrocarbon at a minimum expense to the consumer, at the same time affording perfect safety from explosion and freedom from offensive odors; and the invention consists in certain novel features of construction and combinations of parts, which 15 20 will be hereinafter described, and pointed out in the claims.

The accompanying drawing is a view in elevation, partly in section, of my improved machine.

25 A represents a base, and 1 a stand-pipe adapted to contain water up to a given point, as indicated by the numeral 2. This stand-pipe is enlarged at a convenient point to form the chamber 3. In this chamber an oil-tank 30 35 4 is located. This tank is sufficiently less in size than the chamber 3, in which it is located, to leave a space all around it for the circulation of water to keep the contents of the tank perfectly cool at all times and avoid all danger of explosions. The tank is centered by spacing-blocks or similar means 5 5, located above and below it, and the tank is 40 filled through oil-filler 6. A pipe 7, having a slightly-enlarged or funnel-shaped mouth 8, leads downward from the bottom of the oil-tank, and the glass gage 9 forms a continuation of this pipe, the design of the gage being of course to indicate to the eye the level 45 of the oil in the tank. Feed-pipe 10 leads from a point preferably just inside of the mouth 8 of the gage upward through the tank and chamber in which the latter is located. The object of this arrangement is to provide for absolutely draining out the last particle 50 of oil should it be desired to do so or should occasion require it. It will be seen that when air-pressure is removed from the oil-supply

any oil which might be in the pipe 10 or in the superheater above it will flow into the tank, and no oil will remain in said pipe above 55 the level of oil in the tank.

At the upper end of the feed-pipe the superheater 12 is located, and above this the vapor-generator 13 is so disposed as to receive vapor from the oil contained in the super- 60 heater 12. Burner 14 surrounds the upper end of the superheater just below the generator 13, and the needle-valve 15 in the pipe leading down from the generator is directed toward this burner, and another needle-valve 65 16 also communicates with the generator and is located in the distribution-pipe.

A pipe 17 leads upward from a point at or near the upper end of the oil-tank, and it is furnished with two branches 18 and 19, branch 70 75 18 leading in the direction of the generator and superheater and terminating with a needle-valve 20, having an air-inlet a short distance below the generator and upper end of the superheater, and the other branch 19 extending downward from the extreme upper end of pipe 17 and extending into the generator. This branch 19 is equipped with a stop-cock 21 for controlling the carbureted air therein. Wicking 22 is placed loosely for 80 85 about ten inches in pipe 17 and coiled around the bottom of the oil-tank. This wicking absorbs oil and by capillary attraction conducts it up into the pipe, so that air forced through the oil in the tank and wicking becomes thoroughly carbureted, the air-pressure being created by means of devices now to be described and being discharged with sufficient force to agitate the oil.

The numeral 25 indicates the air-supply 90 pipe. It leads downward from a point at or near the upper end of the stand-pipe into the upper end of the oil-tank 4, where it preferably has a number of perforations, so that the air will be discharged into the oil-tank in 95 small jets and serve to keep the oil stirred, thus preventing stagnation. A hollow air-compressor 26 is placed over this pipe, and it extends down far enough so that the water contained in the stand-pipe forms a water 100 seal. The compressor is furnished at its upper end with a valve 27. This compressor is weighted sufficiently to give the required pressure to the oil, and so long as this pres-

sure continues a constant level of the oil is maintained in the superheater at the oil-level mark at 28. When the air in the compressor has been exhausted, the compressor can be 5 merely raised and vacuum created is sufficient to open the valve 27 automatically and cause a recharging with a fresh supply of air. The moment the air-pressure is removed the oil recedes from its level in the feed-pipe 10 to the tank below. Then when pressure is restored the oil again rises to the point 28 indicated. At this point I desire to give emphasis to the fact that the apparatus is rendered non-explosive. It is made so by this 15 complete submerging of the oil-tank. This provision against explosion is so complete that if a fire were built around the tank and the oil were heated to produce all the expansion possible, say until it reaches sixteen hundred times its volume, which is the maximum, the effect would be that the vapor would rise in the air-compressor and lift it until its lower open end rises to a point within an inch or so of the surface of the water, the vapor in 25 an effort to escape below the lower edge of the air-compressor would come into contact with the water and immediately condense, being merely vapor and not a fixed gas, and return to its original state—that is, oil. By 30 way of experiment I have repeatedly covered the machine with oil from top to bottom and ignited it to demonstrate this fact.

The operation is as follows: Branch pipe 18 is always filled with carburized air under 35 pressure on account of the constantly-applied air-pressure from the air-compressor. The valve 20 is opened and a light is applied to the end thereof. This light supplies the initial heat to the generator and vaporizes oil in 40 the superheater, the vapor entering the generator. When the generator shall have been sufficiently heated, which only requires about two minutes' time, the supply from pipe 18 will be shut off and valve 15 opened to supply 45 the burner 14 with vapor from the generator, which vapor will burn in said burner all around the top of the superheater, which furnishes the required heat to the superheater and generator. By this provision oil never 50 has to be burned, as heretofore, to generate heat, thus avoiding the unpleasant odor always incident to burning hydrocarbons.

Should gas be required in the distribution-pipe *a*, valve 16 is opened, and it may be mentioned in this connection that gas has been conducted away over a hundred feet from the generator with perfect success. The apparatus is so proportioned and the normal air-pressure is such that the pipe 17 is always 60 supplied with air and oil mixed under pressure, approximately at a ratio of seventy-five to twenty-five. This will be apparent when it is remembered that the air entering the oil-tank 4 is under pressure and that it will find 65 an exit through the pipe 17 and through the loose wicking 22 therein, the air leaving said pipe being thus charged with hydrocarbon.

Therefore after gas is produced in the generator the valve 21 is opened and the carbureted air allowed to enter sufficient to change 70 the ratio to about seventy to thirty.

It is evident that slight changes might be made in the form and arrangement of the several parts described without departing from the spirit and scope of my invention, 75 and hence I do not wish to limit myself to the exact construction herein set forth; but,

Having fully described my invention, what I claim as new, and desire to secure by Letters Patent, is—

1. The combination with an oil-supply tank, a generator and a feed-pipe leading from the oil-supply tank to the generator, of a pipe communicating at one end with the said oil-supply tank and conducting carbureted air 85 directly therefrom to a point in proximity to the generator for supplying fuel for the initial heat for the generator, substantially as set forth.

2. The combination with an oil-tank, a generator and a feed-pipe for conducting oil from the oil-tank to the generator, of a pipe communicating with the upper portion of the oil-tank and adapted to discharge in proximity to the generator, wicking adapted to be immersed in oil in the tank and projecting into 95 said last-mentioned pipe.

3. The combination with an oil-tank, a generator and a feed-pipe for conducting oil from said tank to the generator, of a pipe communicating with the top of the tank, wicking adapted to be immersed in the oil in the tank and extending into said pipe, two branches communicating at one end with said pipe, the other end of one branch terminating under 105 the generator and the other end of the other pipe communicating with the generator, substantially as set forth.

4. The combination with an oil-tank, a generator, a superheater, a burner surrounding 110 the upper end of the superheater, and needle-valve supplied from the generator and arranged to direct its discharge into the burner, of a pipe leading from the tank and provided with absorbent material therein, branch pipes 115 leading from this pipe, one branch leading into the generator and the other terminating in proximity to its lower side, and means for creating a pressure in the several pipes.

5. The combination with a stand-pipe, of 120 an oil-tank disposed between the ends of said stand-pipe so as to be wholly surrounded by water therein, a generator disposed alongside said stand-pipe and a feed-pipe supporting the generator and communicating at one end 125 therewith and at the other end directly with said oil-tank, substantially as set forth.

6. The combination with a stand-pipe having an enlarged chamber and adapted to contain water, of an oil-tank disposed within 130 said enlarged chamber so as to be immersed in the water therein, a generator communicating with said oil-tank, an air-compressor coöperating with said stand-pipe and a valve

for said compressor, constructed to automatically open when the compressor is raised to receive more air, substantially as set forth.

7. The combination with a tank, a pipe leading from the bottom of the latter, said pipe having an enlarged or funnel-shaped mouth, and a gage connected with said pipe, of a feed-pipe leading from the tank at a point within the mouth of the gage-pipe and a generator connected with the other end of the product-pipe.

8. In a gas-machine, the combination with a pipe having an enlarged chamber at its lower end and communicating therewith, of an oil-tank adapted to be submerged in water in said enlarged chamber, an air-compressor over the open upper end of said pipe, the open lower end of said compressor being adapted to be immersed in water in the pipe, whereby when the expansion in the compressor in consequence of heat reaches a given point the vapor will condense by its contact with the water, substantially as set forth.

9. The combination in a gas-machine, of a reservoir, an oil-tank adapted to be immersed in water in said reservoir, and an air-compressor disposed in said reservoir over the water therein and having its lower end adapted to be immersed in the water in the reservoir, substantially as set forth.

10. In a gas-machine, the combination with

an oil-reservoir, of three pipes leading directly upward therefrom, one taking down air and another taking up air and oil together and the third conveying up the oil.

35

11. In a gas-machine, the combination with an oil-reservoir, a generator and a feed-pipe connecting the reservoir to the generator, of an air-pipe discharging into said reservoir, and an air-compressor constructed and adapted to operate automatically by gravity to force air through said air-pipe, substantially as set forth.

40

12. In a gas-machine, the combination with a stand-pipe, an oil-reservoir adapted to be submerged in water therein, and a generator communicating with the oil-reservoir, of a pipe communicating with said reservoir and adapted to discharge against the generator, an air-compressor coöperating with the stand-pipe and a pipe communicating at its upper end with the air-compressor and at its lower end with the oil-tank, substantially as set forth.

50

In testimony whereof I have signed this specification in the presence of two subscribing witnesses.
